FUEL PUMP

Ben G. Parsons, Grosse Pointe, Mich., assignor to
 Fuel Charger Corporation, Detroit, Mich., a
 corporation of Michigan

Application May 4, 1945, Serial No. 591,967

1 Claim. (Cl. 103—2)

1

The present invention relates to improvements in liquid pumping devices and particularly to fuel injectors for use with internal combustion engines.

It is a primary object of the present invention to provide improvements in devices of the type mentioned in which improved means are provided for controlling the amount of liquid delivered during the delivery stroke of the pump plunger.

A further object of the invention is to provide improvements in devices of the type mentioned in which such devices are of a relatively simple construction and may be accurately and quickly produced in mass production.

Other objects, advantages, and features of the present invention will become more clearly apparent from the following description, the drawings relating thereto, and from the claim hereinafter set forth.

In the drawings, in which like numerals are used to designate like parts in the different views throughout:

Figure 1 is a side elevational view of a fuel injector embodying features of the present invention and showing such injector connected to an injector nozzle;

Fig. 2 is an end elevational view of the construction shown in Fig. 1, taken from the right end thereof;

Fig. 3 is an end elevational view of the structure shown in Fig. 1 and taken from the left end thereof;

Fig. 4 is a vertical, cross-sectional view, with parts in elevation, of the structure shown in Fig. 1;

Fig. 5 is a cross-sectional view taken substantially along the line 5—5 of Fig. 4;

Fig. 6 is a cross-sectional view taken substantially along the line 6—6 of Fig. 4;

Fig. 7 is a developed elevational view of the actuating cam employed with the structure shown in Fig. 4;

Fig. 8 is a separated or exploded view of certain of the parts making up the injector assembly, with certain of the parts shown in cross section;

Fig. 9 is a view similar to Fig. 8 and showing the remaining parts as they would be extended from the right end of Fig. 8;

Fig. 10 is a cross-sectional view of the actuating cam;

Fig. 11 is an end elevational view of the drive coupling shown in Fig. 8;

Fig. 12 is a side elevational view of the plunger shown in Fig. 8, and

2

Fig. 13 is a diagrammatic view illustrating the operation of the structure of the present invention.

The structure of the present invention is particularly adapted to be used on the type of injector disclosed in the copending application of Ben G. Parsons Serial No. 568,177, filed December 14, 1944, now Patent Number 2,405,163, dated August 6, 1946, although the broader aspects of the present invention are also applicable to other types of fuel injectors, such as a single plunger, single cylinder type. The structure disclosed in the copending application referred to is a single plunger, multi-cylinder type.

The present invention is illustrated in connection with a fuel injector which employs a single cylinder for distributing liquid fuel, such as gasoline, to a multiplicity of internal combustion engine cylinders. In the particular embodiment illustrated, the pump is designed to distribute to six cylinders, by way of example. It will be obvious that it could be constructed to deliver to more or less cylinders.

The fuel injector is generally indicated at 1 and comprises a plunger body 2 formed with a central axial bore 3 therethrough. The pump body 2 has formed therein a plurality of radially extending and equally spaced inlet bores or ports 4 which open into the bore 3. An annular, external recess or groove 5 is formed around the body 2 and communicates with the outer ends of ports 4. There are six of such ports 4 in the embodiment illustrated.

An inlet tube fitting 6 embraces the pump body 2 around the groove 5 to form an annular inlet chamber therebetween. The fitting 6 has a tubular projection 7 thereon to which a flexible tube or conduit may be connected. The conduit (not shown) leads to the source of fuel supply.

The fitting 6 is mounted on the body 2 and has rubber sealing rings 8 disposed on opposite sides thereof, one of the rings 8 abutting against a shoulder formed on the body 2, and the other ring 8 being disposed between the adjacent faces of the fitting 6 and a sealing ring nut 9. The nut 9 is threaded onto a threaded portion formed on the exterior surface of the body 2.

A plurality of annularly spaced discharge passageways or bores 10 are also formed in the pump body 2, the inner ends of which open into the bore 3. Such openings are in a plane axially spaced from the plane of the inlet ports 4. The opposite ends of passageways 10 communicate with axially extending openings 11 formed in a radially projecting, annular flange 12 of the body

2. There are six of the discharge passageways 10 in the embodiment illustrated, one for each of the engine cylinders. Such passageways 10 are circumferentially aligned between the inlet ports 4. This relationship is best seen from a comparison of Figures 5 and 6.

The injector assembly 1 is adapted to be mounted to the crankcase of the engine, as is disclosed in the above referred to copending application, by means of mounting bolts 13 which are passed through the openings 11. A distributor ring or tube ring 14 is disposed between the flange 12 and the adjacent face of the crankcase. Sealing gaskets 15 are disposed between the facing surfaces of the ring 14, the crankcase, and the flange 12. Washers 15' are disposed between the heads of bolts 13 and the adjacent faces of flange 12. The mounting bolts 19 pass through openings formed in the cam ring 14 and have reduced portions 16, which form, with such openings and the opening 11, an annular chamber into which the corresponding passageways 10 open and communicate.

Distributor tubes or conduits 16, there being one for each cylinder, are fixedly mounted on the ring 14 and lead to their respective injector nozzles 17. Such nozzles are of the pressure responsive opening type disclosed in the copending application of Ben G. Parsons, Serial No. 546,352, filed July 24, 1944, now abandoned, which open to admit fluid to the cylinder at a predetermined nozzle opening pressure.

A hollow delivery plunger 18 is rotatably and reciprocably disposed within bore 3 and has an opening through the inner end thereof which is in open communication with the bore 3. The space within the hollow plunger is indicated at 19. The plunger 18 is formed with a plurality of equally spaced inlet openings 20 through the wall thereof adjacent the open end and communicating with chamber 19. There are six of such openings 20 in the embodiment illustrated, one corresponding to each of the inlet ports 4 and having the same equal spacing. The plunger 18 is also formed with a single delivery opening 21 through the wall thereof which communicates with chamber 19 and which is axially spaced from the ports 20 and disposed circumferentially between two of the ports 20, as best shown in Figs. 4 and 8. The opening 21 is adapted to register with the inner open ends of ports or passageways 10 in succession, in a manner that will become more apparent from the following description, and in the manner disclosed in the above mentioned application Serial No. 568,177.

The plunger 18 is rotated and reciprocated within the bore 3 to effect delivery of the fuel through the delivery passageways 10 in succession. The closed end of the plunger 18 has transversely extending tongue 22 with a curved end 23. The plunger 18 and tongue 22 project beyond the bore 3 within an enlarged space formed by an integral annular portion 24 of the pump body 2.

A drive coupling 25 is disposed within the flange 24 and has a groove 26 formed in one end thereof which receives the tongue 22 therein. The opposite side of the coupling 25 has a groove 27 formed therein, which is displaced 90° from the groove 26 and which is adapted to be connected to the source of power for rotating the coupling 25 as disclosed in the above mentioned application Serial No. 568,177. The plunger 18 is thus rotated upon rotation of the drive coupling 25. The reduced end 23 formed on the

tongue 22 is provided so that alignment of the plunger 18 within the bore 3 is not disturbed upon rotation of the coupling 25.

The coupling 25 has a pair of diametrically opposed stub axles 28 formed thereon which serve to mount rollers 30. The rollers 30 are retained on the stub axles 28 by means of snap rings 31. The rollers 30 are constantly held against the cam surface 32 of a cam ring 33. Cam surface 32 is designed to effect proper reciprocation of the plunger 18 upon rotation thereof, in the present instance being designed with six crests and troughs. The cam ring 33 is mounted within the flange 24 and is held against axial displacement by means of a snap ring 34 which is received within an annular internal groove formed in the flange 24. The cam 33 is located in its proper rotative position by means of a locating pin 35 which is received within a groove 36 in flange 24 and projects within an opening formed in the cam ring 33.

It will thus be seen that upon rotation of the coupling 25 the plunger 18 is caused to rotate and reciprocate. When the rollers 30 are on the crests of cam 32, the plunger 18 is at the beginning of the inlet or suction stroke; and the six inlet openings 4 are overlapped with the inlet openings 20 in the plunger to provide inlet communication with the interior space 19. At this time, there is no communication between the distributor openings 21 and any of the passageways 10, since the passageways 10 are aligned with ports 4 and opening 21 is displaced with respect to openings 20. When the rollers 30 are in the troughs of cam 32, the plunger 18 is at the end of the intake stroke and the beginning of the delivery stroke. Further rotation of the plunger 18 brings the opening 21 into communication with one of the passageways 10. At this time the ports 4 are closed off. There are thus six cycles of reciprocation of the plunger for each rotation thereof so that for one rotation of the plunger the opening 21 is brought into communication with all of the passageways 10 in succession.

A coil spring 38 is disposed within the hollow plunger 18 with one end bearing against a centering button 39, which in turn seats within the end of space 19. The opposite end of the spring 38 abuts against a shoulder 40 formed in the body 2 adjacent the end of bore 3. Axial opening 41 communicates the bore 3 with a pressure chamber 42, formed in the body 2. The bore 41 adjacent the pressure chamber 42 is formed with an annular valve seat 43 and a hollow valve 44 is disposed within the bore 41. Such valve 44 has an annular tapered portion 45 adapted to seat on valve seat 43. An annular groove 46 is also formed in the valve 44 and a pair of diametrically opposed openings 47 are formed through the wall of the valve 44 in the base of recess 46, communicating with the interior hollow portion of the valve.

The valve is urged toward the valve seat 43 by means of a coil spring 48, one end of which bears against the closed end of the valve and the opposite end of which bears against the inner surface of a control nut 49. The control nut 49 is threadably received onto an externally threaded portion of pump body 2. A control lever 50 is fixed to the nut 49 and may be rotated to control the spring pressure exerted on the valve 44 to urge it against its valve seat and to close communication between the bore 3 and chamber 42.

Passageways 51 are formed in the valve body

2 which communicate with the chamber 42 and communicate with each of the ports 4, there being one of such passageways 51 for each of the ports 4. Thus, when the valve 44 is opened, fluid delivered by the plunger 18 will pass through opening 47 into chamber 42 and back to the inlet ports through passageways 50. The point at which such valve 44 is opened will thus determine the amount of fuel delivered through opening 21 during the delivery stroke of the plunger 18. If the nut 49 is turned so that pressure exerted on it by the fuel pressure, built up during the delivery stroke of the piston 18, is less than the nozzle opening pressure, that is, the opening pressure of injector nozzle 17, all of the fuel delivered by plunger 18 will be returned to the inlet ports through passageways 51. By adjusting the nut 49, the pressure required to open the valve 44 may be varied, so that if it is set above nozzle opening pressure, all the fuel will be delivered through the openings 21 and to the cylinders through the nozzles. At any intermediate setting of the nut 49, the valve 44 is opened and fuel is returned through the passageways 51 until nozzle opening pressure is reached. After the plunger develops pressures higher than nozzle opening pressures, the fluid is introduced into the cylinders through the nozzles. Thus, by adjusting nut 49, the amount of fuel delivered through the nozzles may be adjustably set. The relationship of the different settings of nut 49 to vary the spring pressure in comparison with the nozzle opening pressure is illustrated in Fig. 13.

In the operation of the device above described, and assuming that the nut 49 is set for opening at a pressure above nozzle opening pressure, fuel is constantly supplied through the tube 7 so that there is a constant supply of fuel within space 5 and within the inlet ports 4. With the plunger 18 in such a rotative position that the rollers 30 are on the crests of cam 32, the plunger is at the beginning of its intake stroke. As the rollers 30 move toward the troughs of the cam, the plunger 18 moves toward the left, viewing Fig. 4, with the openings 20 overlapping and communicating with inlet ports 4. Fuel is thus drawn into the space 19. When the rollers 30 reach the troughs in the cam 32, the plunger is at the end of the intake stroke and at the beginning of the delivery stroke. Further rotation of the plunger 18 causes the rollers to move to the crests of the cam, and at the beginning of such movement communication between open-

ings 20 and 4 is cut off, and opening 21 communicates with one of the passageways 10 delivering fuel to the injector nozzle 17 associated with that passageway through its particular conduit 16. As soon as nozzle opening pressure is reached, fuel is then delivered through the nozzle to its particular cylinder during those degrees of rotation of the plunger while the particular pressure above nozzle opening pressure is maintained. A uniform charge of fuel is thus delivered through the opening 21 to the delivery ports 4 in succession as the plunger 18 rotates and reciprocates, for a particular setting of the nut 49. The stroke of the piston 18 is constant, but the amount of fuel delivered through the nozzle may be adjustably controlled by adjusting the nut 49, which in effect adjusts the pressure responsive opening of valve 44.

What is claimed is:

20 In a fuel pump having a pump body, a longitudinal bore within said body, inlet ports through said body communicating with said bore, delivery ports through said body axially spaced from said inlet ports and communicating with said bore, a hollow delivery plunger disposed within said bore, means in said plunger communicating the interior of said plunger with the inlet ports, means in said plunger communicating the interior of the plunger with said delivery ports in succession, means to reciprocate and rotate said plunger to effect delivery of fuel through said delivery ports in succession, and adjustable pressure responsive valve means directly communicable with said bore for controlling the amount of fuel delivered through the delivery port in each delivery stroke of the piston.
